US00D551041S

(12) **United States Design Patent** (10) Patent No.: **US D551,041 S**
(45) Date of Patent: **** Sep. 18, 2007**

(54) **POTTERY TOOL**

(76) Inventor: **Arthur R. Park**, 1126 Hoffman Ave.,
Royal Oak, MI (US) 48067

(**) Term: **14 Years**

(21) Appl. No.: **29/215,857**

(22) Filed: **Oct. 26, 2004**

(51) LOC (8) Cl. **08-05**

(52) U.S. Cl. **D8/19**

(58) Field of Classification Search **D8/14, D8/16, 19, 45, 88, 499; D2/609; D7/300.2; D19/35, 41, 45, 46, 54, 100; D21/722, 725, D21/729, 731; D24/119, 136; 2/255, 256; 366/342, 343**

See application file for complete search history.
